Patented Nov. 27, 1917.

C. E. GREGORY

By Watson E. Coleman

Attorney

UNITED STATES PATENT OFFICE.

CHARLES E. GREGORY, OF STAMPING GROUND, KENTUCKY.

CONVERTIBLE WAGON-BODY.

1,247,823.

Specification of Letters Patent. Patented Nov. 27, 1917.

Application filed May 19, 1917. Serial No. 169,704.

To all whom it may concern:

Be it known that I, CHARLES E. GREGORY, a citizen of the United States, residing at Stamping Ground, in the county of Scott and State of Kentucky, have invented certain new and useful Improvements in Convertible Wagon-Bodies, of which the following is a specification, reference being had to the accompanying drawings.

10 This invention relates to an improved convertible wagon body, and has for its primary object to provide means for easily and quickly converting the body of a wagon or similar vehicle for use either for ordinary transportation purposes or as a hay rack.

15 It is another and more particular object of the invention to provide an improved mounting and arrangement of adjustable side and end boards which may be easily 20 and quickly disposed in outwardly inclined positions or secured in vertical upright positions upon the fixed side and end boards of the wagon body.

25 It is another important object of the invention to provide an improved detachable hay rack and means for easily and quickly arranging the same in operative position with respect to the wagon body or removing it therefrom.

30 And it is a further general object of my invention to provide a convertible wagon body as above characterized, which is simple and durable in its construction, entirely practical as well as highly serviceable and convenient in use, and capable of manufacture at relatively small cost.

With the above and other objects in view, my invention consists in the novel features of construction, combination and arrangement of parts to be hereinafter more fully described, claimed and illustrated in the accompanying drawing, in which,

Figure 1 is a perspective view of my improved wagon body showing the adjustable side and end boards in their upright positions;

Fig. 2 is a fragmentary perspective view of one end of the wagon body with the detachable hay rack mounted in position;

Fig. 3 is a detail vertical section showing an auxiliary end board mounted between the adjustable side boards of the wagon body; and

Fig. 4 is an enlarged elevation showing the locking means for the adjustable body boards in its released condition.

Referring in detail to the drawing, 5 designates the floor or bed of a wagon body, to the sides and ends of which the longitudinal and transverse vertically disposed boards 6 and 7 respectively are suitably secured. To each of these side and end boards, the spaced, vertically disposed, metal strap bars 8 are securely bolted or riveted, the lower portions of said bars being bent or returned 65 upon themselves to provide elongated loops 9. These loops serve as guides for the elongated, U-shaped rods 10, the purpose of which will be presently explained.

11 and 12 respectively indicate the adjustable side and end boards of the wagon body, and upon the outer face of each of these boards, the spaced metal strap bars 13 are secured. These bars, at one of their ends, are hingedly connected, as shown at 14, to the upper ends of the metal straps 8 on the fixed side and end boards 6 and 7. The other ends of the straps 13 are provided with sleeves 15. The terminals of each of the U-shaped rods 10 are connected by a bolt 16 80 which is loosely engaged to rotate in the sleeve 15 of one of the strap bars 13. The medial portion of the rod 10 has free sliding movement in the elongated guide loop 9. Thus, when the side and end boards are 85 moved to outwardly inclined positions as seen in Fig. 2, the medial portion of the U-shaped rod 10 bears upon the lower closed end of the loop 9 and constitutes a rigid strut or brace for the adjustable side and end boards.

For the purpose of securely clamping and holding the side and end boards 11 and 12 in their erect or upright positions upon the fixed boards 6 and 7 of the wagon body, I 95 provide upon the outer side of each of the end boards 12 and adjacent to the opposite ends thereof, a lever 17 having an angular inner end portion 18 which is pivoted at its extremity, as at 19, upon the board 12. The 100 other end of the lever 17 terminates in a hook 20 which is adapted for engagement through the eye of a bolt 21 which is fixed in the adjacent end of one of the side boards 11. Links 22 are pivotally connected at one 105 of their ends, as at 23, to the respective levers 17 at the juncture of the angular end portion 18 to the body of the lever. The other ends of the links 22 are connected at spaced points to an operating lever 24, said 110 lever preferably being of the form shown and having a suitable operating handle 25

formed upon one end. When the lever 24 is in the position seen in Fig. 4 of the drawing, it will be observed that the levers 17 are moved laterally in an outward direction upon the end board so that the hooks 20 thereof are elevated. The adjustable side and end boards 11 and 12 being now raised to upright positions upon the corresponding fixed side and end boards 6 and 7 of the wagon body, the operator throws the lever 24 over to the position seen in Fig. 1 of the drawing, thus moving the pivotal connections between said levers and the links 22 past each other and drawing the levers 17 inwardly and downwardly so as to engage their terminal hooks 20 in the respective eye-bolts 21 fixed to the sides 11 of the wagon body. Thus, the side and end boards 11 and 12 are rigidly secured or held in contact with each other in their vertical or upright positions. As soon as the lever 24 is raised to release the hooks from the eye-bolts, the several side and end boards 11 and 12 swing outwardly to the inclined positions shown in Fig. 2, such movement being limited by the bracing rods 10 engaging with the lower closed ends of the guide loops 9 as above stated.

If desired, either or both ends of the wagon body may be provided with an auxiliary end board indicated at 26 which, when the end boards 12 are disposed in their outwardly inclined positions, can be inserted above the fixed end boards 7. This auxiliary end board 26 is also provided with a holding device similar to that above described, and the hooks 20 of said device may be engaged in the eye-bolts 21 on the adjustable side boards 11 to hold the latter in their upright positions. Thus, the outwardly inclined end board 12 will constitute a step or support which is of convenience in loading or unloading the vehicle.

In connection with my improved convertible wagon body, I also employ a detachable hay rack shown in Fig. 2 of the drawing. This rack includes spaced uprights 27 which are connected by one or more horizontal bars 28. To the lower ends of the uprights 27, the metal strap bars 31 are fixed, said strap bars extending beneath said uprights and having the angularly disposed, medial portions 32. Braces 33 are secured to the lower ends of the uprights 27 and to the angular portions 32 of the strap bars 31. The free ends of these strap bars are vertically disposed and terminate in the hooks 34. These hooks are adapted for engagement under a rod 35 which is fixed in the eye-bolts 36 secured in the floor or bed 5 of the wagon body. In the use of the hay racks, they may be arranged at one or both ends of the wagon body and, if desired, also along the sides thereof. The side and end boards 11 and 12 are first disposed in their

outwardly inclined positions and the rack member is then arranged in position within the wagon body and the hooks 34 engaged over the rod 35. The rack is then swung upwardly, the hooks turning freely on said rod until the rack is disposed in a vertical position with the inclined medial portions 32 of the strap bars 31 resting upon the upper surface of the adjustable end board 12. Thus, the wagon body may be readily converted for use as a hay rack or in the transportation of various other commodities.

From the foregoing description, taken in connection with the accompanying drawing, the construction, manner of use and several advantages of the invention will be clearly and fully understood. It will be seen that I have devised a very simple and serviceable vehicle or wagon construction wherein the several adjustments may be easily and quickly made. In practical use, the convertible wagon body has been found very serviceable for general transportation purposes required in farm work. It will, of course, be manifest that the adjustable side and end boards of the wagon body can be of any desired width, and the guide loops 9 can also be of various lengths so that the adjustable side and end boards will be supported at the desired inclination. I have above referred to a particular form and construction of the detachable hay rack, but it is manifest that this detachable rack is capable of considerable variation. The rack can be very easily and quickly arranged in position or removed simply by swinging the same inwardly and downwardly from the floor of the wagon so that the hooks 34 can then be disengaged from the rod 35. When in use, the rack is very strongly braced and sustained in its erect position. The various other elements above referred to are also susceptible of considerable modification and it is, therefore, to be understood that I reserve the privilege of adopting all such legitimate changes as may be fairly embodied within the spirit and scope of the invention as claimed.

Having thus fully described my invention, what I desire to claim and secure by Letters Patent is:

1. The combination with a wagon body having fixed side and end boards, of adjustable side and end boards hingedly mounted upon the upper edges of the body boards, means for limiting the movement of the adjustable boards to outwardly inclined positions with respect to the body boards, spaced levers having angular ends pivotally mounted upon each of the adjustable end boards, the other ends of said levers terminating in hooks, an operating lever, links operatively connecting said angular levers to the operating lever, eye-bolts fixed in the adjustable side boards for

engagement by said hooks when the operating lever is moved in one direction, whereby the adjustable side and end boards are retained in vertical upright positions upon the body boards, and an auxiliary end board adapted to be arranged above the fixed end board of the wagon body and also having retaining means for engagement with the eye bolts on the adjustable side 10 boards to hold the latter in their vertical positions when the adjustable end board is disposed in an outwardly inclined position.

2. The combination with a wagon body having adjustable side and end boards, of a 15 hay rack including spaced uprights, metal

strap bars fixed to the lower ends of said uprights, said metal straps terminating in hooks at one of their ends, each of said strap bars having an angular portion to rest upon the angular surface of one of the 20 adjustable boards of the wagon body, and a rod mounted above the floor of the wagon body for detachable engagement by said hooks.

In testimony whereof I hereunto affix my 25 signature in the presence of two witnesses.

CHARLES E. GREGORY.
